AIRPLANE

Alexander M. Lippisch, Cedar Rapids, Iowa

Application April 13, 1953, Serial No. 24,480

Term of patent 14 years

(Cl. D71—1)

To all whom it may concern:

Be it known that I, Alexander M. Lippisch, a citizen of Germany, residing at Cedar Rapids, State of Iowa, have invented a new, original, and ornamental Design for an Airplane, of which the following is a specification, reference being had to the accompanying drawing, forming a part hereof.

This application is a continuation-in-part of my copending application Serial Number D-17,097, filed October 24, 1951, now abandoned.

Figure 1 is a front elevational view of an airplane showing my new design;

Figure 2 is a top plan view, and

Figure 3 is a side elevational view thereof.

I claim:

The ornamental design for an airplane as shown.

ALEXANDER M. LIPPISCH.
